(57) **ABSTRACT**

The instant invention provides a fitness equipment for facilitating both push up and wriggling excises without occupying a large storage space. The instant invention discloses a push-up twisting plate; which is made up of two circular, rotating bases and each base has a detachable handle. The handles can be easily removed by the user by applying a rotational force on the handle and an opposing rotational force on the base. To assemble the push-up twisting plate, the user can repeat the same motion, but in reverse.

a top layer comprising:
 a top center opening; and
 a connecting port, wherein said connecting port
 comprises a wide portion and a narrow portion;
 a middle layer comprising:
 a middle center opening,
 an inner ball bearing ring; and
 an outer ball bearing ring; and
 a bottom layer comprising:
 a bottom center protruding structure;
 an inner track corresponding to said inner ball bearing ring; and
 an outer track corresponding to said outer ball bearing ring;
 wherein said bottom center protruding structure protrudes through said middle center opening and said top center opening, and said connecting port is positioned above and between said outer ball bearing ring and said inner ball bearing ring; and

wherein said anchoring portion attaches into said connecting port when said detachable handle is attaching to said top layer, wherein said connecting leg is inserted into said wide portion, and then slides into and locked at said narrow portion.
 5. 2. The push-up twisting plate with said detachable handle according to claim 1, wherein said top layer further comprising a first annular track and a center jack.
 3. The push-up twisting plate with said detachable handle according to claim 1, wherein said bottom layer further comprising a second annular track and a center pole.
 4. The push-up twisting plate with said detachable handle according to claim 3, wherein said middle layer further comprising a ball groove for accommodating track ball.
 10 5. The push-up twisting plate with said detachable handle according to claim 4, wherein said top layer and said bottom layer are sandwiching said middle layer, and said top layer and said bottom layer are rotating via over said track ball when said track ball rolls in said second annular track.
